UNITED STATES PATENT OFFICE.

JOSEPH E. PERRAULT, OF WALTHAM, MASSACHUSETTS, ASSIGNOR TO JUDSON L. THOMSON MFG. CO., A CORPORATION OF MAINE.

MACHINE FOR SETTING RIVETS.

No. 879,805.

Specification of Letters Patent.

Patented Feb. 25, 1908.

Application filed February 21, 1907. Serial No. 368,614.

To all whom it may concern:

Be it known that I, JOSEPH E. PERRAULT, a citizen of the United States, residing at Waltham, in the county of Middlesex and State of Massachusetts, have invented new and useful Improvements in Machines for Setting Rivets, of which the following is a specification.

This invention relates to machines for setting rivets or the like in leather or other sheet material.

The object of the invention is to provide an improved means for guiding the rivet from the raceway to the carrier or holder in which it is held prior to being driven in the stock by a suitable driver. In machines of this class in which rivets or the like are employed which are fed from a hopper down a raceway to a carrier or other receptacle in which the rivet is placed before being driven, the rivet is very liable, in passing from the raceway to said carrier to tip over and enter the carrier with the shank of the rivet projecting upwardly instead of downwardly as is desired. This is especially liable to occur when the rivet has a large head and short shank and it is one of the objects of this invention to provide a device which shall prevent the rivet from tipping over, as hereinbefore set forth, and to hold the same in correct position to enter the carrier from the raceway with the head uppermost and leave the same in said carrier in proper position to be driven into the stock by the driver.

It is further the object of this invention to provide a device of the character set forth which may be adapted to rivets having different sized heads and different length shanks, and it is also to be understood that the device of this invention may be adapted to articles other than rivets, such as tacks, nails, hinging hooks, boot buttons, et cetera.

The object of this invention is further to provide an improved raceway for delivering the rivets to the carrier.

The invention consists in the combination and arrangement of parts set forth in the following specification and particularly pointed out in the claims thereof.

Referring to the drawings: Figure 1 is a left hand side elevation of a rivet setting machine embodying my invention, the same being partly broken away and shown in section. Fig. 2 is an enlarged front elevation, broken away to save space in the drawings, of the

raceway and mechanism for carrying the rivets from said raceway to the material in which they are to be driven and driving mechanism by means of which said rivets are inserted in said material and clenched therein. Fig. 3 is a side elevation viewed from the right of Fig. 2. In Figs. 2 and 3 the rivet carrier and driver are shown raised. Fig. 4 is a front elevation similar to Fig. 2, with the driver and carrier lowered in position to set the rivet in the leather. Fig. 5 is a side elevation as viewed from the right of Fig. 4, the anvil being partly shown in section. Fig. 6 is a sectional elevation taken on line 6—6 of Fig. 3, as viewed from the left of said figure. Fig. 7 is a sectional elevation taken on line 7—7 of Fig. 6. Fig. 8 is a sectional plan taken on line 8—8 of Fig. 6. Fig. 9 is a detail front elevation broken away and shown in section of the raceway foot. Fig. 10 is a right hand side elevation of said raceway foot. Fig. 11 is a section taken on line 11—11 of Fig. 9, the same being broken away to save space. Fig. 12 is a plan view of the rivet feeding slide with a rivet shown in connection therewith. Fig. 13 is a detail front elevation of said slide.

Like numerals refer to like parts throughout the several views of the drawings.

In the drawings, 20 is the frame of the machine, 21 a driver-slide adapted to slide in ways 22 and having a driver 23 fast thereto. The driver-slide 21 has a reciprocatory motion imparted thereto by a lever 24 connected to said driver by a link 25, said lever 24 being pivoted at 26 to the frame 20. The lever 24 is rocked upon its pivot 26 by means of a foot treadle and spring (not shown in the drawings) said lever being connected to said treadle by means of a link 27. The downward motion of the rear end of the lever 24 is limited by a stop 28 having screw-threaded engagement with the frame 20, whereby the upward motion of the driver-slide 21 and driver 23 is regulated.

The rivets 29, 29, 29 are fed from a hopper 30 to a raceway 31, said raceway consisting of an upper part 32 formed of strips of steel fastened by screws to the outer face of a bracket 33, fast to the head and a lower part 34 consisting of a plate fastened to the inner face of said bracket 33. The plate 34 constitutes a foot and has a V-shaped groove 35 adapted to guide said rivets 29 from the upper part 32 of the raceway to the carrier 36.

The groove 35 extends downwardly across the lower end of the foot 34 at an angle thereto and has a second groove 37 extending horizontally thereacross which intersects the 5 rivet guiding groove 35, the outer guide walls 38 of the rivet-guiding groove 35 extending upwardly beyond the bottom of the groove 37, as at 39, this upward extension of the outer guide walls 38 being in alignment 10 with and constituting part of the outer wall 39 of the horizontal groove 37. The groove 35 is located at the left of the space or groove 40 in the upper part of the raceway (Fig. 5) and as the rivets 29 descend said upper part 15 of the raceway the lowermost rivet in the upper part of the raceway rests against a slide 41 adapted to be moved longitudinally thereof in the groove 37.

The slide 41 has a T-shaped slot 42 extending transversely thereacross and a reciprocatory motion is imparted to said slide by a 20 spring arm 43, the lower end of which projects into a slot 44 in the slide 41, the upper end of said spring arm being fastened to the 25 lower end of a lever 45 pivoted at 46 to the frame of the machine, the upper arm of said lever 45 being held in contact with a rocking lever 47 by a spring 48. A rocking motion is 30 imparted to the lever 47 by suitable mechanism, thus imparting a rocking motion to the lever 45 and a reciprocatory motion to the slide 41. As the rivets descend the upper 35 part 32 of the raceway 31, the lowermost rivet in said upper part is carried by the slide 41 from said upper part into alignment with the groove 35 in the foot 34 and sliding down said groove passes to the carrier 36.

The carrier 36 consists of two side plates 49, 49, each provided in its upper end with 40 a semi-annular groove 50 to receive the head of the rivet after it has passed from the raceway to said carrier, and beneath said semi-annular grooves, between the plates 49, 49 is a chamber 49'. Each of the plates 49, 49 is 45 fastened to a flat spring 51, said flat spring being fastened by means of a bolt 52 and nut 53 to the carrier slide 54. The carrier slide 54 is adapted to slide in ways 55 formed in the head 56 of the frame 20 and is moved upwardly by a spiral spring 57, the lower end of which is fastened to a screw 58 fast to said carrier slide, the upper end of said spring being fastened by a screw 59 to the head 56.

The material 60 into which the rivet is to 55 be clenched is supported upon an anvil 61 which, in turn, is adjustably supported upon an arm 62 forming a portion of the frame 20.

A guide-finger 63 is pivoted at 64 to the carrier slide 54. The inner edge 65 of the 60 finger 63 is inclined at an angle, at 66, to the driver 23 and bears against the lower end of said driver, as will be seen in Fig. 6, said inner edge being held preferably in contact with said driver by a spiral spring 67, one end 66 of which bears against the outer edge of the

guide-finger 63, the other end of said spring bearing against a plate 68 fast to the carrier slide 54. It will be noted that the guide-finger 63 is located in a slot or groove 69 extending longitudinally of the slide 54 and 70 opening out of the inner face thereof. It will be seen that as the rivets 29 descend the lower portion 34 of the raceway and pass to the rivet carrier 36 they are very liable to tip and enter said carrier in an inverted or partly 75 inverted position, as hereinbefore set forth. This is entirely obviated by the finger 63, the lower end of which is located in the exact position to allow the rivet to slide freely from the lower part of the raceway into the carrier, but will prevent the same from tipping over by reason of the lowermost end of said finger touching the top of the head of the rivet as it is passing from the raceway to the carrier and thus guiding it and keeping it in 80 correct position to finally land the head uppermost in the groove 50 in readiness to be driven, as hereinafter described.

In feeding rivets of different sizes or forms it becomes necessary to adjust the guide-finger 63 so that the lower end thereof will 90 approach the lower end of the groove 35 more nearly or may be carried farther away therefrom in order to correctly guide the rivets, as set forth. To accomplish this adjustment of the guide-finger a variety of 95 means may be employed without departing from the spirit of my invention. One very simple means is to limit the upward movement of the driver-slide 21 and driver 23 by 100 limiting the downward movement of the rear end of the lever 24 which can be conveniently accomplished by means of the stop-screw 28 (Fig. 1). While I have illustrated and described this particular embodiment of my 105 invention constructed with a guide-finger having an inclined inner edge 65 bearing against the lower end of the driver 23, it is evident that this inclined or cam-shaped surface, by means of which the guide-finger is 110 actuated and its position with relation to the rivets regulated, may be located at any desirable portion of the guide-finger 63 and that it is not necessary that said inclined portion should have contact with the driver itself.

The general operation of the mechanism hereinbefore specifically described and illustrated in the drawings in Figs. 1 to 13 is as follows: The rivets are fed from the hopper 30 to the upper part 32 of the raceway 31 by 120 any of the well known means for this purpose, and sliding down said upper part of the raceway in the groove 40 the lowermost rivet will rest upon the upper edge of the slide 41. Said slide has a reciprocatory motion imparted thereto by the levers 47, 45 and arm 43 and when the same has been moved backwardly or to the right into the position illustrated in Fig. 3, said lowermost rivet will drop into the T-shaped slot 42. 130

When said slide is moved from the position illustrated in Fig. 3 to that illustrated in Fig. 5, the rivet in the Y-slot 42 will slide down the groove 35 in the lower part or 5 foot 34 of the raceway and from thence will pass beneath the guide-finger 63 between the side plates 49 of the carrier 36, with the head thereof resting in the groove 50. The operator now depresses the 10 treadle which, through the link 27, rocks the lever 24 upon its pivot 26 in the proper direction to move the driver-slide 21 and driver 23 downwardly. The lower end of the driver abuts against the head of the rivet 15 located in the rivet carrier and pushes said rivet carrier downwardly, together with the side 54, against the action of the spring 57 until the lower ends of the plates 49 abut against the material 60 resting upon the anvil 61. At this point in the cycle of operations further downward motion of the carrier is arrested and as the driver is forced still further downward the rivet is pushed downwardly between the plates 49, 49, the 20 rivet head forcing said plates apart sufficiently to allow of its passage downwardly therebetween. Said rivet is then driven through the material and clenched upon the anvil 61, as illustrated in Fig. 5. When the 25 operator releases the treadle the different parts will assume the relative positions illustrated in Figs. 2 and 3.

As the grooves 35 and 37 are both formed in a solid piece of steel, there is no possibility 30 of the lower end of the raceway becoming bent and thrown out of alinement with the carrier to which it is feeding rivets.

Having thus described my invention, what I claim and desire by Letters Patent to set 35 out is:

1. In a machine for driving rivets and the like, a raceway, a carrier adapted to receive a rivet or the like from said raceway, a movable guide-finger adapted to engage the head 45 of said rivet as it passes from said raceway to said carrier, and adjustable means adapted to locate said finger relatively to said raceway and carrier as said rivet is passing from said raceway to said carrier.

2. In a rivet setting machine, a reciprocating driver, a raceway, a rivet carrier provided with a chamber adapted to receive a rivet, a finger pivoted to said carrier, the free end of said finger normally located above 55 said chamber with its inner edge inclined at an angle to and bearing against the lower end of said driver, means to hold said finger in sliding contact with said driver, and a stop to limit the upward movement of said driver, whereby the relative location of the free end of said finger to said chamber and raceway may be determined.

3. In a machine for driving rivets and the like a raceway, a reciprocating carrier 60 adapted to receive a rivet from said raceway,

a reciprocatory driver, a guide-finger pivoted to said carrier, the free end of said finger normally located above said chamber, with its upper edge inclined to and bearing against the lower end of said driver, means to hold said finger in sliding contact with said driver, means to stop said carrier during the upward movement of said driver, and means to subsequently stop the upward movement of said driver, whereby the relative location of said finger to said raceway and carrier is changed and determined during the last part of the upward movement of said driver.

4. In a machine for feeding and driving rivets and the like, a raceway terminating at the lower end thereof in a foot, said foot consisting of a plate adapted to be fastened to a stationary member, and having a groove adapted to guide said rivets or the like, extending downwardly across the lower end 85 thereof at an angle thereto.

5. In a machine for feeding and driving rivets and the like, a raceway terminating at the lower end thereof in a foot, said foot consisting of a plate adapted to be fastened to a 90 stationary member, and having a groove adapted to guide said rivets or the like, extending downwardly across the lower end thereof at an angle thereto, and having a second groove extending horizontally there- 95 across and intersecting said rivet-guiding groove.

6. In a machine for feeding and driving rivets and the like, a raceway terminating at the lower end thereof in a foot said foot consisting of a plate adapted to be fastened to a stationary member, and having a groove 100 adapted to guide said rivets or the like, extending downwardly across the lower end thereof at an angle thereto, and having a 105 second groove extending horizontally there- across and intersecting said rivet guiding groove, the outer guide walls of said rivet- guiding groove extending upwardly beyond the bottom of said second groove in alinement with an outer wall of said second groove extending longitudinally thereof.

7. In a machine for feeding and driving rivets and the like, a raceway terminating at the lower end thereof in a foot, said foot consisting of a plate adapted to be fastened to a stationary member, and having a groove 115 adapted to guide said rivets or the like, extending downwardly across the lower end thereof at an angle thereto, and having a 120 second groove extending horizontally there- across and intersecting said rivet-guiding groove, and a slide in said second groove adapted to move a rivet longitudinally there- of into alinement with said rivet-guiding 125 groove.

8. In a rivet feeding and driving machine, a reciprocating driver, a stationary member, a raceway consisting of an upper part fast to the outer face of said stationary member and 130

a foot consisting of a plate fast to the inner face of said stationary member adjacent to said driver, and having a groove adapted to guide said rivets or the like extending across the lower end thereof at an angle thereto and terminating at its upper end adjacent to said upper part of said raceway.

In testimony whereof I have hereunto set my hand in presence of two subscribing witnesses.
